UNITED STATES PATENT OFFICE.

ELMER E. MCGUIRE, OF ANACONDA, MONTANA, ASSIGNOR OF ONE-THIRD TO JOSEPH SMITH, OF ANACONDA, MONTANA.

FASTENING-PIN.

1,209,867.

Specification of Letters Patent. Patented Dec. 26, 1916.

Application filed May 12, 1915, Serial No. 27,653. Renewed April 29, 1916. Serial No. 94,482.

To all whom it may concern:

Be it known that I, ELMER E. MCGUIRE, a citizen of the United States, residing at Anaconda, in the county of Deerlodge and State of Montana, have invented certain new and useful Improvements in Fastening-Pins, of which the following is a specification, reference being had to the accompanying drawings.

10 This invention relates to certain new and useful improvements in fastening pins and more particularly to a pin of this character adapted to be used on clevises and is provided with means whereby no matter what 15 position the clevis assumes, the fastening pin will be securely held against withdrawal.

Another object of the present invention is the provision of a device of the above character which will possess advantages in points 20 of efficiency and durability, is inexpensive to manufacture and, at the same time, is simple in construction and operation.

With the above and other objects in view, the invention consists in the novel features 25 of construction, combination and arrangement of parts as will be hereinafter referred to and more particularly pointed out in the specification and claims.

In the accompanying drawing forming a 30 part of this application, Figure 1 is a view in side elevation of a fastening pin constructed in accordance with my invention, illustrating the application of the same.

Fig. 2 is a sectional view illustrating the 35 manner of arranging the pintles as herein embodied when it is desired to insert or withdraw the pin from applied position; Fig. 3 is a detail sectional view illustrating the position of the pintles when the pin is 40 in vertical position; and Fig. 4 is a detail sectional view illustrating the positions of the pintles when the pin is in a horizontal position.

My improved fastening pin, as illustrated 45 in the accompanying drawing, is shown as applied to a conventional clevis. This fastening pin includes an elongated body 1 cylindrical in cross section and provided at one end with a head 2 which may be of any 50 desired form. The outer end of the pin as illustrated, is bifurcated to form spaced arms 3 and extending transversely through these arms and across the space therebe-

tween, is a pivot pin 4, the purpose of which will be hereinafter more fully set forth. 55 Movably mounted between the arms 3, are the locking pintles or keys 5 and 6, which are mounted for pivotal movement upon the transverse pin 4. It will be noted that the locking pintle or key 5 is mounted upon the 60 pivot pin so that one end portion of the pintle or key is substantially longer than the other end, while the pintle or key 6 is mounted at its longitudinal center upon the pivot pin with its opposite end portions of a 65 length substantially equal to the length of the shorter end portion of the key 5, so that no matter what position the fastening pin 1 assumes, the longer end of the pintle 5 will drop down. It will also be noted that the 70 opening through the pintle 6 is elongated and disposed transversely of the pintle so that when the body 1 is disposed in a horizontal position, as disclosed in Fig. 4, the pintle 6 will automatically assume the horizontal position. Thus, as shown in Fig. 3, 75 when the fastening pin 1 is disposed in a vertical position the longer end of the locking pintle 5 will cause the same to drop and be disposed in parallel relation with the 80 arms 3 but, on the other hand, the locking pintle 6 will be arranged transversely across the bifurcation of the fastening pin and engage the side of the object to which the pin is applied to prevent the withdrawal or removal of the pin.

In Fig. 4 the pin is shown as disposed in a horizontal plane and, in this view the locking pintle 6 is disposed parallel with the arm 3, while the pintle 5 is arranged transversely 90 across the opening in which the pin is mounted to prevent the removal of the same. Thus, it will be apparent that no matter what position the fastening pin 1 assumes, one or the other of the locking pintles 5 and 95 6 will be disposed transversely across the opening in which the pin is mounted, but it will be seen that the fastening pin 1 can be quickly and readily removed from any device to which it is applied by arranging the 100 locking pintles 5 and 6 in longitudinal alignment with the body of the pin so that they will be disposed directly between the two arms 3.

From the above description taken in connection with the accompanying drawing, it

will be apparent that I have provided a simple and durable fastening pin which is provided with locking pintles pivotally mounted within one end of the pin in such a manner that no matter what position the pin assumes, one of these locking pintles will be disposed in such position that it will be impossible to withdraw the fastening pin 1. Thus it will be noted that my improved 10 fastening pin can be used in any place where a pin of this character can be applied but it is preferable to have the same applied to use wherein it is desired to have a pin which can be quickly and readily inserted or withdrawn. It is preferred, however, to use the same on clevises, for the well known clevis pin in use at the present time.

My improved device, as herein shown and described, is extremely simple in construction and can be manufactured and placed upon the market at a comparatively low cost.

While I have shown and described the preferred form of my invention, it will be obvious that various changes in the details of construction and in the proportions may be resorted to for successfully carrying my invention into practice, without sacrificing any of the novel features or departing from the scope of the invention as defined by the appended claims.

Having thus described this invention,

what I desire to claim and secure by Letters Patent is:—

1. As a new article of manufacture, a 35 fastening pin bifurcated at one extremity, locking pintles pivotally mounted within the bifurcated portion of the pin and normally disposed in angular relation to each other, said pintles being capable of independent 40 movement.

2. As a new article of manufacture, a fastening pin bifurcated at one extremity, locking pintles pivotally mounted within the bifurcated portion of the pin and normally 45 disposed in angular relation to each other, said pintles being capable of independent gravitational movement.

3. As a new article of manufacture, a fastening pin having one end portion bifurcated, a pivot pin intersecting the kerf of the bifurcated end portion, locking pintles 50 rotatably supported by the pivot pin and independently movable therearound, one of said pintles being provided with a transversely disposed elongated opening through 55 which the pivot pin is disposed.

In testimony whereof I hereunto affix my signature in the presence of two witnesses.

ELMER E. McGUIRE.
